UNITED STATES PATENT OFFICE.

JAMES G. WILSON, OF NEW YORK, N. Y., ASSIGNOR, BY MESNE ASSIGNMENTS, TO UNION SEAMLESS KNITTING MACHINE COMPANY.

IMPROVEMENT IN KNITTING-MACHINES.

Specification forming part of Letters Patent No. 55,434, dated June 5, 1866.

To all whom it may concern:

Be it known that I, JAMES G. WILSON, of the city, county, and State of New York, have invented certain new and useful Improvements in Knitting Machinery; and I do hereby declare that the following is a full, clear, and exact description of the same, reference being had to the accompanying drawings, forming part of this specification, in which—

Figure 1 is a central vertical section of a circular-knitting machine with my improvements. Fig. 2 is a plan of the same. Fig. 3 is a horizontal section of the same in a plane passing very near the bottom of the needle-ring. Fig. 4 is a horizontal section of the needle-ring in the plane indicated by the line $\alpha\alpha$ in Fig. 1. Fig. 5 is a side view of the cam and its appendages for producing the rotary movement of the needle-ring. Fig. 6 is a back view of the needle-ring and its stationary casing.

Similar letters of reference indicate corresponding parts in the several figures.

This invention consists in the employment, for the purpose of controlling the direction and changes of direction of the rotating movement of the needle-ring of a circular-knitting machine about its axis, or for the purpose of changing the direction of the movement of the needle-bar of a straight-knitting machine, of a studded wheel which has no movement in a direction parallel with its axis and which makes but one revolution to effect all the changes in the movement of the needle-ring necessary to complete a stocking or any other knitted article.

It also consists in certain novel mechanism through which the said wheel acts to cause the movement of the needle-ring upon its axis in a circular machine or the longitudinal movement of the needle-bar in a straight machine to take place in one direction or the other; also, in a certain novel system of needles by which the knitting is enabled to be performed at one and the same time with separate and distinct yarns on several immediately adjacent needles.

And it further consists in a certain mode of combining yarn-guides and a presser with the aforesaid studded wheel and longitudinally-moving series of needles.

To enable others skilled in the art to make and use my invention, I will proceed to describe its construction and operation.

A is a bed-plate, which, with its supporting standards B B, constitutes the framing of the machine. C is the needle-ring fitted to rotate in a suitable bearing, half of which is formed by a semicircular recess in the bed-plate A, and the other half in a bow, D, bolted to the bed-plate by bolts aa . This ring, whose general form is that of an upright cylinder, has its exterior grooved longitudinally for the reception of the needles bb , which are represented of the flexible bearded kind common to the oldest knitting-machines, but which may be of other kinds, the said needles being fitted to slide freely up and down in the said grooves, and being confined therein by a stationary cylindrical casing, E, which fits loosely over the ring, and which is secured to the bed-plate A in any suitable manner. The depth of the grooved portion of the needle-ring is equal to or slightly greater than the length of the needles, so that the needles may be received entirely within the needle-ring and the casing E, as shown at the right-hand side of the needle-ring in Fig. 1. The needles are each made with two outward projections, cc' , on the lower parts of the outer sides of their shanks, for the reception between them of the edge of a plate, F, (see Figs. 1 and 4,) which is attached to a lever, G, working on a fixed fulcrum, d , for the purpose of producing the necessary longitudinal movement of the needles. The lower part of the stationary casing E is enlarged, as shown in Fig. 1, to make room for the projections cc' on the needles, and a shoulder, e , is formed inside of it, where the enlargement commences, the height of such shoulder being such that it just allows the upper projections, cc' , of the needles to pass under it when the needles are entirely within the ring, and prevents the needles rising while in any position excepting when opposite to an opening, ff , provided in the back of the casing E, as shown in Figs. 1, 4, and 6, for the reception of the plate F, the said opening being wide enough to expose at one time the shanks of one more than the number of needles upon which it is desired to knit simultaneously, and the length of the said plate being sufficient to enable it to enter between the projections cc' of all the so exposed needles. The rotating motion of the needle-ring is intermittent, and the longitudinal movement up and down of those needles which are opposite the opening

ff alternates with the rotating movement of the ring and the whole series of needles; and the distances of the latter movements are sufficient to carry one needle away from the opening *ff* and present another needle opposite to the said opening. The plate *F*, instead of being made to pass between two projections on the needles, may be grooved longitudinally to receive single projections on the needles.

To provide for the rotating motion of the needle-ring it is furnished round its lower end with teeth *g g*, to be operated upon by one of two pawls, *h h'*, attached by pins *j j'* to a slide, *H*, which is fitted to fixed horizontal guides *i i* under the bed-plate, and which derives a movement back and forth in the said guides from a grooved cam, *I*, on the horizontal main shaft *J* of the machine, the groove 10 (see Fig. 5) in the said cam receiving an anti-friction roller, *k*, secured to the said slide. The said pawls *h h'* are situated on opposite sides of the needle-ring, and have springs *l l'* applied to them in such manner as to exert a constant tendency to make them engage with the teeth *g g*, but one or other of them is always held out of gear by one of the arms of a forked or three-armed lever, *K L L'*, which is arranged below the slide *H* on a fixed fulcrum-pin, *m*, secured in the bed-plate, said fulcrum passing through a slot, *n*, (see Fig. 3,) provided for it in the slide *H*. The needle-ring will be caused to rotate in one direction or the other, according as the pawl *h* or *h'* is in gear with the teeth *g g*.

Fig. 3 shows *h'* in gear and the needle-ring rotating in the direction of the arrow marked upon it, but by a movement of the arm *K* of the lever *K L L'* in the direction of the arrow marked upon its extremity the arm *L'* of the said lever is caused to throw the pawl *h'* out of gear, and the arm *L* of the said lever is caused to permit the spring *l* to throw *h* into gear, and so the direction of the rotation of the needle-ring is caused to be reversed by the shifting of the said lever, for which purpose the arm *K* of the said lever is situated directly over the studded wheel or drum *M*, which constitutes one of the most important features of this invention, such wheel being secured immovably to a horizontal shaft, *N*, which is fitted to rotate in fixed bearings at the back of the machine, but which is permitted no longitudinal motion. This wheel has but a narrow surface, as it only requires to have two rows of studs, *p p* and *p' p'*, one row to act upon an inclined surface, *q*, (see Figs. 2 and 3,) on one side of the arm *K* of the lever *K L L'*, for the purpose of shifting the lever in one direction, and the other row to act upon a similar inclined surface, *q'*, on the opposite side of the said arm, to shift the lever in the other direction. The said studs *p p* and *p' p'* are provided in such number and arranged at such distances apart on the wheel *M* that the said wheel, making one complete revolution in the direction of the arrows shown on it in Figs. 1 and 2, while a stocking or other com-

plete article is being knitted, will shift the lever whenever it becomes necessary or desirable to reverse the rotary motion of the needle-ring—as, for instance, in knitting the toe and heel of a stocking. The revolution of the said wheel is intended to be very slow, except when a stud, *p* or *p'*, arrives in a position to act upon the lever *K L L'*, when it must be moved quickly far enough to enable the stud to effect the necessary movement of the lever.

The slow movement is effected by the action of a pawl, *O*, on a series of very fine ratchet-teeth, *r r*, with which the wheel is provided all round one side of its rim, the said pawl being attached to a lever, *O'*, which works horizontally on a fixed fulcrum, *s*, secured to the bed-plate *A*, and the said lever deriving its movement on its fulcrum from its connection, by a rod, *t*, with a crank-wrist, *t*, carried by a spur-gear, *P*, which is fitted to rotate on a fixed stud, *t'*, secured to the bed-plate, and which gears with a pinion, *P'*, of much smaller size, on the main shaft. The wheel is moved by these means only to the extent of one tooth of the ratchet for each revolution of the gear *P*, which makes but one revolution for about four of the main shaft. The quicker movements, which take place whenever a stud, *p* or *p'*, arrives in position to act upon the lever *K L L'*, are produced by the action upon such stud itself of a pawl, *Q*, which is secured to the slide *H* by a screw, *x*. As soon as a stud passes this pawl, with the movement effected by the action of the pawl *O* on the ratchet-teeth *r r*, the said pawl *Q* drops behind the said stud, and the next backward movement of the slide *H*, produced by the cam *I*, brings the said pawl into action upon the said stud, and so forces the stud against the inclined surface *q* or *q'* of the lever and effects the shifting thereof. The pawls *O* and *Q* both work through guides *v* under the bed-plate. The pawl *Q* is forked for the lever *K L L'* to pass through it.

To prevent the accidental shifting of the lever, a locking-spring, *R*, is applied to press upon it, but this spring and the part of the lever on which it acts is beveled so that the lever can press it upward to pass it when the studs *p p'* come into operation on it.

The operation of the lever *G* to give the needles the movement upward to the position shown at the left-hand side of the needle-ring in Fig. 1, and down again to a position within the ring like that shown at the right-hand side of the ring and its casing in the same figure, is effected by means of a grooved cam, *S*, on the main shaft *J*, the groove 12 in the said cam receiving a pin, *w*, which is secured in a rod, *G'*, attached to the lever *G*, and which is also connected by a bridle-rod, *w'*, with a fixed pin, *w''*, secured to the bed-plate.

The cam is so formed that during one quarter of each revolution it raises the needles from within the ring, during the next quarter it leaves them stationary in their elevated position, during the third quarter it lowers them,

and during the last quarter it leaves them stationary within the ring.

The rotating movement of the ring takes place while the needles are stationary in their lowest position. The projections *c c'* then meet with no obstruction, but pass regularly, one at a time, onto the plate *F* as they are presented opposite the opening *f f* in the case *E*.

U is a horizontal rock-shaft arranged in bearings in standards *U' U'* erected upon the back part of the bed-plate *A*. This rock-shaft has two arms, *U² U²*, connected by a plate, *U⁴*, which both carries the yarn-guides *y y* and the presser *T*; and the rock-shaft has a third arm, *U³*, which carries an anti-friction roller, *15*, which is received in a groove, *13*, in a cam, *V*, on the main shaft. The yarn-conductors consist simply of eyes attached rigidly to the front edge of a plate, *y'*, which is secured to the plate *U⁴* by screws *14 14*. The number of conductors is equal to the number of needles upon which it is intended to knit at once, or, in other words, one less than the number of adjacent needles raised simultaneously by the operation of the lever *G*, and they are arranged at distances apart corresponding with the distances between the needles. The presser *T* consists of a bar or plate having its front edge turned downward and curved to conform to a circle circumscribing the needles, the length of the said bar or plate being sufficient to enable it to operate simultaneously on as many immediately adjacent needles as are raised simultaneously by the lever *G*. It is secured to the plate *U⁴* below the yarn-conductor plate *y'* by the same screws *14 14* which secure the latter plate, the said screws passing through slots in *U⁴* and *y'* and screwing into tapped holes in the presser, the slots providing for the adjustment of the yarn conductors and presser in a backward and forward direction. The cam *V*, by its action on the roller *15*, gives the yarn-conductors and presser a movement obliquely downward and forward toward the needles and back again, the forward and downward movement taking place just before the descent of the needles, and the return or backward and upward movement taking place while the needles are in their lowest position and the needle-ring is making its rotary movement. The yarns, one for each needle and conductor, are supplied from separate spools arranged in any suitable position. The downward and forward movement of the yarn-conductors and presser toward the needles brings the yarn-conductors to such a position relatively to the needles that the needles in their descent will receive their threads to form a series of loops, and brings the presser into such a position that after the needles have received the threads their flexible beards, by coming in contact with the presser, will be closed to enable them to pass into the loops last formed upon them, and hence will be caused to carry the new series of loops through the old ones and slip out of

or cast off the old ones. The backward and upward movement of the yarn-conductors and presser simply takes them out of the way of the yarns and needles. The yarn-conductors require a lateral movement every time the direction of the rotation of the needle-ring is changed, in order that they may severally be always in proper relation to the needles which are receiving the yarn from them. This movement is produced by connecting the arm *U³* of the rock-shaft *U* with the lever *K L L'* by a rod, *W*, which causes the rock-shaft, every time the said lever is shifted, to derive a proper longitudinal movement in one direction or the other, as may be required.

In operating with a machine fitted with a studded wheel, *M*, as described, for the purpose of controlling and changing the direction of the revolution of the needle-ring, the knitting may be commenced in any part of a stocking or other article, according to the position in which the wheel *M* may happen to be; but as the said wheel may be turned by hand in the direction of the arrow marked upon it, it may be always brought to the most convenient or favorable position for commencing the article. This kind of wheel, and the means described for combining it with the needle-ring, may be used in connection with needles having no flexible beards and having no longitudinal motion.

The operation of the within-described circular system of flexible bearded needles and presser will have been understood by the foregoing description to resemble, in a great degree, the operation of the corresponding parts of the old-fashioned English knitting-machine; but the operation of the said system of needles, in connection with the yarn-conductors, will have been understood to resemble that of the corresponding parts of another well-known kind of knitting-machine. The system of needles, yarn-conductors and presser represented is intended to combine the best characteristics of both those kinds of machines in such manner as to make a very simple and at the same a very perfect working and rapidly-operating machine.

In a former application for Letters Patent I have described and claimed the combination of yarn-conductors, needles, pressers, and stitch-hooks for knitting with separate yarns on two or more immediately adjacent or consecutive needles, the object of such combination being to knit more rapidly than can be done by the machines previously known and to produce work of better quality. The result effected by the invention herein described—viz., the knitting with separate yarns on immediately adjacent or consecutive needles—is the same, but the means of carrying it out are much more simple. The same result may, however, be accomplished by a variety of mechanical devices, and therefore I have desired to be understood in my previous application as claiming, broadly, the first discovery of an organized system of needles and yarn-conductors and their adjuncts for carrying out such result. The speci-

fication of that application describes a system of needles having no longitudinal movement, but this specification describes a system of needles having a reciprocating longitudinal movement, which enables the result to be obtained with less mechanism, and the present invention may therefore be regarded as a further carrying out of or an improvement upon my former one.

The value of the discovery of a mode of knitting upon immediately adjacent or consecutive needles is made apparent from the fact that it enables at least three stockings to be knit in the same time that one was knit by machines having similar elements to that described in my last application, prior to that discovery.

The latch-needle in common use may be applied and used in the within-described machine in substantially the same manner as the flexible bearded needle.

The same system of needles and yarn-conductors, with the whole of the within-described actuating and controlling mechanism, may be adapted to a straight machine; and for knitting drawers and shirts or any other straight or tubular fabrics, for which a reciprocating movement or change of direction of the needle-ring or needle-bar is unnecessary, the whole of the needles used in a machine constructed according to this invention may be made to move up and down at once, and the yarn-guides, one for every needle, may be made to oscillate just far enough to throw the yarn under the hook or beard of each needle. For example, a needle-ring or needle-bar having five hundred needles in it, and having a reciprocating motion at a speed of about five hundred strokes per minute, making five hundred stitches per minute on each needle, (which is less than the usual speed of the machine,) would produce two hundred and fifty thousand stitches per minute, and hence this machine must be capable of knitting much more quickly than any other machine in use.

What I claim as my invention, and desire to secure by Letters Patent, is an organized machine for knitting, composed of elements substantially as detailed by the following separate claims, numbered from 1 to 11.

1. The employment, for the purpose of controlling the direction and changes of direction of the rotary motion of the needle-ring or needle-bar of a knitting-machine, of a studded wheel or drum so constructed, applied, and operating that it performs its duty without any movement in a direction parallel with its axis, as herein described.

2. So constructing and operating the aforesaid wheel or drum, having no movement in a direction parallel with its axis, that it will

make but one revolution during the operation of making a complete stocking or other knitted article, as herein specified.

3. Combining the aforesaid studded wheel or drum, having no movement parallel with its axis, with a slide, H, and pawls h h' , or their equivalents, which produce the rotary movement of the needle-ring of a circular-knitting machine by means of a three-armed lever, K L L', constructed, applied, and operating substantially as herein specified.

4. Giving the studded wheel or drum a compound rotary motion, viz., a slow motion to bring its studs to an operative position and a quicker motion to produce the action of its studs upon the needle-ring or needle-bar, substantially as herein described.

5. The employment, in a circular or straight knitting machine of the specified kind herein described, of a system of needles having longitudinal and lateral movements alternately, and operating substantially as herein specified.

6. The combination, with a system of needles having a longitudinal reciprocating motion, when used in a machine constructed specifically as herein described, of a system of yarn-conductors so applied as to deliver yarn to immediately adjacent or consecutive needles, substantially as herein specified.

7. The plate F, either fitting between two projections, e e' , on the needles, as represented in the drawings, or, what is equivalent, grooved to receive single projections on the needles, and operating substantially as and for the purpose herein specified.

8. The vibrating presser, applied and operating in combination with a laterally and longitudinally moving series of needles, substantially as herein specified.

9. Combining the yarn-guides and presser, substantially as herein specified, to be operated by the same mechanism.

10. The combination of a system of needles and a system of yarn-guides operating automatically, in conjunction with a yielding compressor and bridge for carrying and removing the needles, without the use of stitch-hooks for taking off the stitches, in such manner as to knit simultaneously on two or more immediately adjacent or consecutive needles, substantially as herein described.

11. The combination of the studded wheel or drum M, having no movement parallel with its axis, and a series of needles and yarn-conductors so applied as to effect the knitting simultaneously with separate yarns on immediately adjacent needles.

JAMES G. WILSON.
